Primary Examiner — Ryan Harvey(74) *Attorney, Agent, or Firm* — Lerner, David, Littenberg, Krumholz & Mentlik, LLP(57) **CLAIM**

The ornamental design for an exercise tire frame, as shown and described.

DESCRIPTION

FIG. 1 is a front top perspective view of an exercise tire frame;

FIG. 2 is a rear perspective view thereof;

FIG. 3 is a top view thereof;

FIG. 4 is a bottom view thereof;

FIG. 5 is a left side elevational view thereof;

FIG. 6 is a right side elevational view thereof;

FIG. 7 is a front elevational view thereof; and,

FIG. 8 is a rear elevational view thereof.

The broken lines illustrate unclaimed structure and form no part of the claimed design.
